UNITED STATES PATENT OFFICE.

HARRY THOS. WILLIAMS-EATON, OF SEATTLE, WASHINGTON, ASSIGNOR, BY MESNE ASSIGNMENTS, TO NATIONAL AUTOMATIC FENDER COMPANY, OF SEATTLE, WASHINGTON, A CORPORATION.

CAR-FENDER.

1,130,651.

Specification of Letters Patent.

Patented Mar. 2, 1915.

Application filed June 29, 1912. Serial No. 706,783.

To all whom it may concern:

Be it known that I, HARRY T. WILLIAMS-EATON, a citizen of the United States, residing at Seattle, in the county of King and 5 State of Washington, have invented certain new and useful Improvements in Car-Fenders; and I do hereby declare the following to be a full, clear, and exact description of the invention, such as will enable 10 others skilled in the art to which it appertains to make and use the same.

This invention relates to car fenders and has for an object to provide a fender ordinarily supported at some distance above the 15 road bed, with improved means for dropping the fender to operative position when an obstruction is encountered.

A further object of the invention is to provide a fender having a leaf supported in 20 inclined position under normal conditions, with improved means for dropping said leaf to horizontal position when the main frame is dropped to pick up an obstruction upon the track.

25 A further object of the invention is to provide improved means for supporting the main frame.

A further object of the invention is to provide improved means for retracting and 30 lowering the rear edge of the main frame when released.

With these and other objects in view the invention comprises certain novel constructions, combinations and arrangement of 35 parts as will be hereinafter more fully described and claimed.

In the drawings: Figure 1 is a top plan view of the improved fender attached to a conventional car in operative position. Fig. 40 2 is a view in end elevation of the fender attached to a conventional car shown in operative position in full lines and in dropped or "pick up" position in dotted lines. Fig. 3 is a detail view of the support engaging 45 means showing in full lines the latched position and in dotted lines the unlatched position.

Like characters of reference indicate corresponding parts throughout the several 50 views.

The improved fender which forms the subject matter of this application comprises a back frame whose side bars 10 are secured to a car in any approved and convenient 55 manner as by the use of brackets 11 having

upturned ends 12 and socket members 13 carried by the back frame. The frame is provided with cross bars 14 to produce a coarse fabric back and is stationary upon the car. To the lower ends of said bars 10 at 60 9 are pivoted the rear ends of links 15 which are rigidly connected by a cross bar 16, and the brackets 11 are connected by contractile springs 17 with the lower side of the cross bar at the points 6. To the front ends of 65 the links 15 are pivoted by knuckle-joints 5 the extremities of a U-shaped main frame 18 comprising a front and two end pieces preferably though not necessarily integral, the front piece extending transversely across 70 the track indicated by the rails 19. Hinged to the front piece of the frame 18 is a leaf consisting of side pieces 20 and cross pieces 21 and 22, filled with some material as the rods 23. The side pieces 20 are provided 75 with shoes 24 adapted to ride upon the rails when the frame 18 is dropped and retracted by the action of the springs 17, as indicated in dotted lines at Fig. 2.

To support the main frame 18 in full line 80 position as shown at Figs. 1 and 2, a chain 25 is provided secured to the top of the back frame 10 and extending downwardly to the front cross piece of the main frame 18. To the frame 18 a rod 26 is secured in any approved manner as by the brackets 27, and sleeves 28 and 29 are mounted to slide thereon. One of the sleeves, as 28, is provided with a ring 30 and the other with ears 31 between which is pivoted a pin 32 adapted to 85 90 be engaged by the ring 30. In normal position as shown at Fig. 3 the tip of the pin 32 is engaged by the ring 30 and an eye 33 carried by the chain 25 is engaged with the body of the pin to support the frame 18. 95 The chain 25 is preferably passed under the rear frame piece 21 to support the leaf in inclined position as shown at Fig. 2, and a branch chain 34 extends downwardly to an eye 35 carried by the cross bar 16. 100

To maintain the pin 32 in engagement with the ring 30 levers 36 are pivotally secured to eyes 37 carried by the frame 18 and their rear ends held normally yieldingly toward each other by a spring 38. The levers also carry adjacent their rear ends links 39 and 40, the former engaging the sleeve 28 and the latter engaging the sleeve 29 so that under the tension of the spring 38 the sleeves 28 and 29 are held yieldingly toward each 105 110

other. The levers 36 curve outwardly about the ends of the main frame 18 and extend in front of such frame as indicated at Figs. 1 and 2 and the forward ends are connected by a flexible cord or cable 41.

It will be apparent that with the parts associated as shown in the drawings the frame 18 and the leaf hinged thereto will be supported above the track in the position shown in full lines at Fig. 2. The distribution of weight on the frame 18 tends to hold the forward heavier end down. The chain 25, having connection with said forward end, is therefore kept sufficiently taut to prevent the lighter rear portion of frame 18 (supported by chain 34, bar 16 and links 15) from dropping below the full line position in Fig. 2 until the chain 25 is released. When the flexible cord 41 strikes an obstruction upon the track it serves to draw together the forward ends of the levers 36 and spread apart the rear ends of such levers thereby, by reason of the links 39 and 40 drawing apart the sleeves 28 and 29 as shown in dotted lines at Fig. 3, permitting the tip of the pin 32 to leave the ring 30 and the eye 33 to slip off. The releasing of the eye 33 slackens the chain 25 and permits the frame 18 to drop by gravity and also permits the spring 17 to act to drop the cross bar 16 and the links carried thereby, so that the frame 18 is both retracted and dropped to the position shown in dotted lines at Fig. 2 to pick up from the track any object thereon. The parts are of course returned to normal position by simply raising the forward end of the main frame 18 and putting the eye 33 over the pin 32, spreading apart the sleeves 28 and 29 by pushing against the flexible cord 41, and then releasing such cord to permit the ring 30 to engage the tip of the pin 32. The leaf is then dropped upon the chain 25 to supporting position as shown at Fig. 2.

45 I claim:—

1. In a fender, a back frame adapted to be connected with a car, links pivoted to the bottom of the back frame, a main frame pivoted to the front ends of the links, means 50 to retract the links, means to hold the main frame in elevated position and the links in forward position, and obstacle engaging means to release the holding means when such obstacle is encountered.

55 2. In a fender, a back frame adapted to be rigidly connected with a car, links pivoted at their rear ends to the lower edge of the back frame, a spring adapted to normally retract the links, a main frame, 60 knuckle-joints connecting it to the front ends of the links, a chain extending from the top of the back frame to the forward end of the main frame, a branch member extending from the chain intermediate its ends to support the links against the tension

of the spring, and means for releasing the forward end of the chain from said frame.

3. In a fender, a plurality of frames, links pivotally connecting their adjacent edges whereby one frame is movable with reference to the other, a chain extending from the top of one of the frames to the forward end of the other frame, a branch chain extending from the first-named chain and connected with a cross bar connecting the 75 links, keepers slideable along the forward edge of the frame last mentioned and arranged to engage the first-named chain, levers for holding the keepers normally in engagement, and a cord carried by the levers 80 in advance of the frames and adapted to actuate the levers to release the keepers.

4. In a fender, a member adapted to be fixedly secured to a car, a main frame disposed in front of said member, links pivotally connecting said frame and member, a spring for retracting links, means to hold the main frame in elevated position and to hold the links against the tension of the spring, levers carried by the main frame, a 90 cord carried by the levers and extending in front of the main frame, and means carried by the levers for releasing the holding means.

5. In a fender, the combination with a 95 back frame adapted to be carried by the car, links pivoted to said back frame, and springs tending normally to swing the links downward around their pivots; of a main frame, knuckle-joints between it and the 100 front ends of said links, a chain attached to the upper edge of said back frame, a latch detachably connecting its front end with the center of said main frame, means for tripping said latch when an obstacle is encountered, and a branch chain connecting the mid-length of the main chain with a cross bar connecting said links, for the purpose set forth.

6. In a fender, the combination with a 110 back frame adapted to be carried by the car, a pair of links pivoted to the lower extremities of the side-bars of said back frame, a cross bar rigidly connecting said links, and springs connecting the lower side of said 115 cross bar with the car and tending normally to swing the links downward around their pivots; of a U-shaped main frame, knuckle-joints between its extremities and the front ends of said links, a chain attached to the 120 upper edge of said back frame, a latch detachably connecting its front end with the center of said U-frame, means for tripping said latch when an obstacle is encountered, and a branch chain connecting the mid-length of the main chain with said cross bar, for the purpose set forth.

7. In a fender, the combination with a 125 back frame adapted to be carried by the car; of a main frame, hinge connections be- 130

tween its rear edge and the lower end of said back frame, a cross rod within said main frame, sleeves slidably mounted on the rod, one of them carrying a ring, a pin pivoted 5 to the other sleeve and having its tip adapted to engage said ring, means pressing said sleeves normally toward each other, means to separate them when an obstacle is struck, and a chain connected with the upper edge 10 of the back frame and having an eye adapted to be engaged by said pin, for the purpose set forth.

8. In a fender, the combination with a back frame adapted to be carried by the car, 15 a pair of links pivoted to the side-bars of said back frame, a cross bar rigidly connecting said links, and springs connecting the lower side of said cross bar with the car and tending normally to swing the links down- 20 ward around their pivots; of a U-shaped main frame, knuckle-joints between its extremities and the front ends of said links, a cross rod within said U-frame, sleeves slidably mounted thereon, one of them carrying a 25 ring and the other ears, a pin pivoted between said ears and having its tip adapted to engage said ring, means pressing said sleeves normally toward each other, means to separate them when an obstacle is struck, 30 and a chain connected with the upper edge of the back frame and having an eye adapted to be engaged by said pin, and a branch chain leading from the mid-length of the main chain to said cross bar, for the purpose 35 set forth.

9. In a fender, the combination with a back frame adapted to be carried by the car, a pair of links pivoted to said back frame, a cross bar rigidly connecting said links, and 40 springs connecting said cross bar with the car and tending normally to swing the links downward around their pivots; of a U-shaped main frame, knuckle-joints between it and the links, a cross rod within said main 45 frame, sleeves slidably mounted thereon, one of them carrying a ring and the other ears, a pin pivoted between said ears and having its tip adapted to engage said ring, levers supported at the sides of said main frame, 50 a contractile spring connecting their rear ends, a flexible element connecting their front ends forward of the main frame, rods

connecting their rear ends with said sleeves respectively, a chain connected with the back frame and having an eye adapted to be 55 engaged by said pin, and a branch chain leading from the mid-length of the main chain to said cross bar, for the purpose set forth.

10. In a fender, the combination with a back frame adapted to be carried by the car; of a main frame, hinge connections between it and said back frame, a cross rod within said main frame, sleeves slidably mounted in said main frame, one of them carrying a 60 ring, a pin pivoted to the other sleeve and having its tip adapted to engage said ring, levers supported by said main frame and connected at their rear ends with said sleeves respectively, a spring connecting the rear 65 ends of the levers, a flexible element connecting their front ends forward of the main frame, and a chain connected with the back frame and having an eye adapted to be 70 engaged by said pin, for the purpose set 75 forth.

11. In a fender, the combination with a back frame adapted to be carried by the car, a pair of links pivoted to said back frame, and springs tending normally to swing the 80 links downward around their pivots; of a main frame, knuckle joints between it and said links, a cross rod within said main frame, sleeves slidably mounted thereon, one of them carrying a ring, a pin pivoted to the 85 other sleeve and having its tip adapted to engage said ring, levers supported by said main frame, a spring connecting their rear ends, a flexible element connecting their front ends forward of the main frame, rods 90 connecting their rear ends with said sleeves respectively, a chain connected with the back frame and having an eye adapted to be engaged by said pin, and a branch chain leading from the mid-length of the main chain 95 and connected to said links, for the purpose set forth.

In testimony whereof I affix my signature in presence of two witnesses.

HARRY THOS. WILLIAMS-EATON.
